United States Patent Office

Des. 197,953
Patented Apr. 14, 1964

197,953

STREET SWEEPER

Carl A. Desens, 1110 Woodman Road, Janesville, Wis.

Filed Feb. 18, 1963, Ser. No. 73,618

Term of patent 3½ years

(Cl. D9—2)

FIG. 1

FIG. 2

FIG. 3

FIG. 4

FIG. 5

FIG. 6

FIG. 1 is a front perspective view of a street sweeper showing my new design;

FIG. 2 is a side elevational view thereof in raised position; the opposite side being substantially plain as best seen in FIGS. 4, 5, and 6;

FIG. 3 is a side elevational view thereof in lowered position;

FIG. 4 is a front elevational view thereof;

FIG. 5 is a bottom plan view thereof; and

FIG. 6 is a top plan view thereof.

The truck shown in broken lines in FIG. 1 and fragmentarily in the remaining views is included for illustrative purposes only.

I claim:

The ornamental design for a street sweeper, as shown and described.
